BUBBLE CAP FASTENING MEANS

George W. Plossl, West Springfield, and William E. Leety, Longmeadow, Mass., assignors to Gilbert & Barker Manufacturing Company, West Springfield, Mass., a corporation of Massachusetts

Application July 19, 1952, Serial No. 299,792

4 Claims. (Cl. 261—114)

1

This invention relates to improved fastening means for use in holding a bubble cap to its chimney and the latter to the floor plate of a tray of a fractionating tower.

The invention has for an object the provision in a bubble cap assembly of improved fastening means for holding the parts together by clamping, which is effected by a bolt and in such a manner that all parts including cap, chimney and clamping elements may be mounted on or demounted from the floor of a bubble tray, rapidly and conveniently, by a single operator working from a position above the floor.

More particularly, the invention has for an object the provision of a member, which is adapted to rest upon the upper end of the chimney, spanning across the chimney opening, and which has means for engaging the hold-down bolt, near its upper end, and temporarily supporting it centralized in the chimney, while the cap is placed over the threaded upper end of the bolt and positioned in proper spaced relation with the chimney and while the retaining nut is applied to the upper end of the bolt.

The invention also has for an object the provision in a bubble cap assembly of a temporary supporting means for the hold-down bolt, which means also serves to support the cap from the chimney, spaced vertically and horizontally therefrom.

The invention will be disclosed with reference to the illustrative embodiment of it in the accompanying drawings, in which:

Fig. 1 is a sectional elevational view of a bubble-cap assembly embodying the invention;

Fig. 2 is a bottom plan view thereof;

Fig. 3 is a sectional plan view taken on the line 3—3 of Fig. 1;

Fig. 4 is an elevational view drawn to a larger scale and showing a stamping from which the hold-down-bolt supporting and cap supporting and spacing means is formed;

Fig. 5 is a top plan view of a bubble cap assembly showing a modification in the form of the combined hold-down-bolt-supporting and cap spacing and supporting means; and

Fig. 6 is a fragmentary sectional elevational view taken on the line 6—6 of Fig. 5.

Referring to these drawings and first to Fig. 1 thereof; the bubble-cap fastening means includes a hold down bolt 1, which is suitably fixed to, and centrally between the ends of, a cross bar 2, commonly called a "strong back." The cross bar 2 is adapted to span an opening 3 in the floor plate 4 of a bubble tray and has horizontal shoulders

2

5 at its ends to abut the lower face of this plate. Preferably also, the upper part of the cross bar is adapted to enter the opening 3 and has vertical shoulders 6 near its ends to engage the inner surface of the peripheral wall 7 of such opening. The chimney 8 at its lower end encompasses the upstanding wall 7 and has an out-turned base flange 9, resting on a suitable gasket 10, which in turn rests on plate 4. The T-bolt fastening member 1, 2 is adapted to be put in place following the mounting of the chimney 8 on plate 4. The operator, holding bolt 1 by its upper end, tilts it and the cross bar 2 until the latter can enter and pass through and below the chimney. Then the bolt 1 must be held in upright position, coaxially of the chimney, with the shoulders 5 of the cross bar located below and approximately parallel with plate 4 and with the shoulders 6 preferably partially entering the lower end of the opening 3 or at least positioned so as to do so, when the bolt 1 is subsequently drawn up by the tightening of a nut 11 applied to the threads 12 on the upper end thereof.

The invention provides a member 13 for temporarily supporting the T-bolt fastener 1, 2 from the upper end of chimney 8, while the cap 14 is being placed in position and nut 11 is being applied to the threads 12 of bolt 1. This member (Fig. 3) is adapted to span across the chimney opening with its outer ends resting upon and supported by the upper end of the chimney. This member 13 has a centrally-located U-shaped portion 15, providing a lateral, open-ended slot 16 of a width such as to slidably fit a cylindrical portion 17 on the shank of bolt 1 near the upper end thereof. The width of this slot is, however, less than the outside diameter of the screw threads 12. At the intersection of the parts 12 and 17 of bolt 1 (Fig. 1) is a shoulder 18. While the operator holds bolt 1 by its upper and screw threaded end in the position above described, he moves the member 13 laterally to carry the U-shaped part 15 into the partially-encompassing relation with the part 17 that is shown in Fig. 3. He then releases his hold on the bolt, allowing it to drop until shoulder 18 rests on the upper end face of the U-shaped portion 15, by which the bolt is supported, during application of the cap 14 and nut 11. The bolt, when thus supported, will have its threaded end positioned sufficiently high to pass through the central hole in the cap and project above the same far enough to allow the nut to be applied thereto.

Preferably, the member 13 is also made to serve as the supporting means and spacing means

for the cap 14. As shown in Fig. 3, this member 13 consists of a plurality of arms 19 radiating from the central U-shaped portion 15 and the outer end of each arm (Fig. 1) has a horizontal shoulder 20, which is adapted to rest upon the upper end face of chimney 8. The cap 14 rests upon the upper edge 21 of each arm. The outer ends 22 of the arms 19 engage the peripheral wall of the cap and center it, as shown in Fig. 3, with reference to the bolt-receiving portion 15 of the supporting structure 13. The arms 19 have vertical shoulders 23 (Fig. 1), which engage the inner surface of the peripheral wall of chimney 8 and locate the structure 13, and in particular the portion 15 thereof, in proper coaxial relation with the chimney.

Conveniently, the supporting structure 13 is made up from stampings of thin sheet metal. One of these stampings is shown at 24 in Fig. 4, on a scale which is twice that of Fig. 3. One stamping, such as shown, is bent into the shape shown in Fig. 3 and thus forms two of the arms 19 and the integral, connecting U-shaped portion 15. Another stamping 24 of the same size and shape is cut along the dotted line 25 to form two single arms 19. One such single arm has its inner end overlapped on one side of the U-shaped part 15 of the two-armed part and suitably secured thereto, as for example by welding. Thus, with three stampings 24, two of the structures 13 can be formed.

Conveniently also, the shoulder 18 on the hold-down bolt 1 may be formed without any material additional expense as an incident to the formation of the screw threads 12 by rolling. Preliminary to the screw-thread rolling operation the upper end of the bolt 1 is run into an extruding die to reduce it to the diameter of the part 17, which is the proper diameter for the formation of the threads 12 by rolling, the rolling operation pressing out the metal as screw threads. Ordinarily, only so much of the bolt is run into the extruding die as is to be screw threaded. In this case, an additional length of the bolt is run into the die but only a part of it is subjected to the screw-thread rolling operation, thus forming the part 17 below the screw threads 12 and the shoulder 18 at the intersection of the parts 12 and 17.

It is necessary in any event to provide spacers between the cap 14 and chimney 8 in order to provide space for the flow of gas between the cap and chimney. Usually, these spacers are rigidly fixed to the cap. This requires the formation of slots in the cap to receive projections from the spacers and the protruding ends of these projections are then headed over to hold the cap and spacer together. By making the spacing means separate from the cap, a saving is made of the cost of forming the slots and the cost of heading over the projections on the spacer and, in addition, the spacing means may then be utilized as a temporary support for the hold-down bolt during assembly or disassembly of the parts. The desirable usefulness of the temporary support for the hold-down bolt may be had by a construction which actually costs less to manufacture than the described former structure which lacked the means for supporting the hold-down bolt during mounting or demounting of the parts. And the new structure of this invention enables substantial savings to be effected in the cost of assembling the parts.

The supporting structure need not necessarily

be constructed with three arms in the manner shown and described in connection with Fig. 3 although that is a very desirable way to do. This structure may, for example, consist of two arms such as shown in Figs. 5 and 6. Here, the temporary support for the hold-down bolt 1 consists of a strip of thin sheet metal which is bent to form a central U-shaped part 26 and two arms 27 extending in opposite directions one from each end of the part 26. The part 26 affords the same open-ended slot to receive the part 17 of the hold-down bolt 1, and the shoulder 18 of the latter is supported by the upper edge of the part 26 in the same way as heretofore described. Suitably fixed to each arm 27, as for example by welding, are two angle brackets 28, which project laterally from the arms 27 in opposite directions and provide broad supporting surfaces for the cap 14. These angles 28 have vertical edges 29 to engage the inner surface of the peripheral wall of chimney 8 and center the U-shaped part 26 therein. The ends 30 of the arms 27 engage the inner surface of the peripheral wall of cap 14 and center the latter with reference to the supporting structure 26, 27.

The particular form of strong back or cross bar 2, shown herein is made up of two strips 31 (Fig. 2) of sheet metal secured together, as for example by welding at two spots as indicated at 32 (Fig. 1). Each strip 31, at a location centrally between its ends, is bent to provide an approximately semi-cylindrical portion 33. The two portions 33 encompass the lower end of the shank of the hold-down bolt 1, as will be clear from Fig. 2. The two parts 33 have oppositely located slots 34 (Fig. 1), which extend therethrough and receive the head 35 of bolt 1. The strong back may, however, be made in any other suitable form.

In use, the various parts of the bubble cap assembly may be mounted on the floor plate of a bubble tray by a single operator working from a position above the tray. Considering the structure shown in Figs. 1, 2 and 3, the operator first places the gasket 10 around the upstanding wall 7 of the hole 3 in floor plate 4 and then places the lower end of a chimney 8 around the wall 7 with the base flange 9 resting on gasket 10. Then, the bolt 1 is held by its upper end and swung until the cross bar 2 is tilted sufficiently to pass down through chimney 8 and slightly below the same. The bolt is then moved into upright position and the upper and more narrow part of the cross bar 2 is partly inserted into hole 3. While the bolt 1 and cross bar 2 are held thus positioned with one hand, the operator with his other hand moves the structure 13 laterally to cause the part 17 of bolt 1 to enter slot 16. The ends of the arms 19 of this structure 13 are then rested on top of chimney 8 and the bolt is released and allowed to drop until its shoulder 18 rests on top of the U-shaped part 15. The bolt 1, being thus supported, the operator puts the cap 14 in position and then applies nut 11 to the threads 12 of the bolt, tightening the nut to draw the cross bar 2 upwardly and press the cap 14 downwardly against arms 19, the latter against chimney 8 and the flange 9 of the latter against gasket 10, forcing the latter against plate 4, whereby the parts are clamped together with single bolt of T-form. This manner of clamping the parts of a bubble cap assembly together is not new but the use of a chimney-spanning member, such as 13, with a central U-shaped part such

5

as 15, to support a shoulder, such as 18 on the hold-down bolt 1, while the operator applies the cap 14 and its retaining nut 11, is new and very useful since it enables quick and convenient assembly of parts by a single operator. By making the cap-spacing and supporting structure separate from the cap, as herein shown, rather than fixed thereto as has been usual heretofore, this same structure can be made to serve as the temporary support for the hold-down bolt 1 by providing the U-shaped part 15 having a lateral, open-ended slot, such as 16.

It will be clear that the structure shown in Figs. 5 and 6 will be assembled in the same manner as the Figs. 1 to 3 structure described.

This invention thus affords a simple structure, well adapted for quantity production at low unit cost, for the purpose of temporarily supporting the hold-down bolt while the cap and retaining nut are applied thereto and preferably also this same structure is used for supporting the cap from and spacing it relatively to the chimney.

What is claimed:

1. In a bubble cap assembly, of the type wherein in the cap, chimney and interposed spacers are clamped together and to the floor of a bubble tray by a bolt, which has a cross bar fixed to its lower end for spanning the lower end of the chimney and engaging the lower face of the floor and which has a nut on its screw-threaded upper end that extends through the cap, the improvement which consists in providing on the bolt below the cap a shoulder and a member having a plurality of arms of thin flat sheet metal radiating from a central U-shaped portion which affords a laterally-extending slot open at one end, said arms near their outer ends being mounted on edge on the upper end of said chimney, said slot receiving a portion of the bolt below said shoulder and having walls on opposite sides thereof underlying said shoulder.

2. The combination, as claimed in claim 1, in which the top wall of the cap rests on the upper edges of the arms to space the cap vertically from the top of the chimney and the outer ends of the arms engage the peripheral wall of the cap to space the cap horizontally from the chimney.

6

3. The combination as claimed in claim 1, wherein said member is composed of one strip of flat thin sheet metal centrally bent to form a U-shaped portion, which affords said slot and the parts on opposite sides thereof, and having two arms extending outwardly one from each end of said U-shaped portion with a portion of the lower edge of each resting on top of said chimney at two angularly spaced locations, and a second strip of half the length of the first strip fixed at one end to said U-shaped portion and extending outwardly with a portion of its lower edge resting on the chimney at a location intermediate and angularly spaced from the two first named locations.

4. In a bubble cap assembly, of the type wherein in the cap, chimney and interposed spacers are clamped together and to the floor of a bubble tray by a bolt, which has a cross bar fixed to its lower end for spanning the lower end of the chimney and engaging the lower face of the floor and which has a nut on its screw-threaded upper end that extends through the cap, the improvement which consists in providing on the bolt below the cap a shoulder and a member supported at its ends on the upper end of the chimney and spanning the chimney opening; said member being engaged with the chimney to hold it from lateral displacement relatively thereto and having a centrally-located slot which receives a portion of said bolt below said shoulder, extends laterally thereof and is open at one end, the walls of said slot engaging the bolt at diametrically opposite locations and at a third location between the first-named locations to center the bolt relatively to the chimney, the upper ends of said walls underlying said shoulder.
